[57] CLAIM

The ornamental design for a frozen treat holder, as shown and described.

DESCRIPTION

FIG. 1 is a top, front, right side perspective view of the frozen treat holder of the present invention;

FIG. 2 is a front elevational view of the frozen treat holder of FIG. 1, the rear being a mirror image thereof;

FIG. 3 is a left side elevational view of the frozen treat holder of FIG. 1;

FIG. 4 is a right side elevational view of the frozen treat holder of FIG. 1;

FIG. 5 is a top plan view of the frozen treat holder of FIG. 1; and,

FIG. 6 is a bottom plan view of the frozen treat holder of FIG. 1.

The drawing is lined for color.
